UNITED STATES PATENT OFFICE.

EDGAR C. WILEY, OF LYNCHBURG, VIRGINIA.

BLOWER.

1,050,892.

Specification of Letters Patent. Patented Jan. 21, 1913.

Application filed October 4, 1909. Serial No. 520,818.

To all whom it may concern:

Be it known that I, EDGAR CLARENCE WILEY, a citizen of the United States, residing at Lynchburg, in the county of Campbell and State of Virginia, have invented certain new and useful Improvements in Blowers, of which the following is a specification.

My present invention relates to steam blowers for furnishing artificial draft to furnaces and the like, and resides particularly in an improved controlling valve therefor.

The essential feature of my device is the use of a secondary valve in conjunction with a steam valve controlling piston, the said secondary valve being so arranged as to admit steam at low pressures to the steam valve controlling piston as the boiler pressure varies. By thus operating this valve controlling piston at a low pressure, I am enabled, as will hereinafter become more apparent, to secure a wider range of movement of the steam controlling valve from a given fluctuation of boiler pressure than could be had were said fluctuation of said boiler pressure allowed to act directly upon said steam valve controlling piston.

With this general statement of the purpose and principle of the device, I will now proceed to a detailed description of the mechanism, reference being had by numeral to the accompanying drawings, wherein,

Figure 1 is an elevation, partly sectional, of a boiler setting and grate with my improved blower mechanism applied; and Fig. 2 is a transverse section of the controlling mechanism, the plane of section being taken through the center line of the device.

Referring to the drawings, 1 represents the boiler shell; 2 the boiler setting; and 3 the grate. These parts may be of any approved construction and are shown merely better to illustrate the mode of applying the blower.

Projecting into the ash pit 4 is the blower tube or draft tube 5, which is embedded in the brick work of the setting 2. Near the outer end of the draft tube is the nozzle which directs the steam jet. This comprises a restricted primary nozzle 11, discharging a jet of steam into the longitudinal passage 6^a of a secondary nozzle 6. Leading into

this passage 6^a are lateral openings 6^b, through which air is drawn into the secondary nozzle by the steam jet leaving the primary nozzle, so that a mixture of steam and air is discharged from the secondary nozzle 6. This results in a larger jet, and induces a greater flow of air through the blower tube.

The secondary nozzle 6 is screwed onto a nipple 10 forming the shell of primary nozzle 11, so that the two are held in proper relative positions. The nipple 10 is formed upon the body of a tubular casting 7, which receives steam from the boiler through a pipe 8. The casting 7 also serves as a support for the nozzle and its valve mechanism, being threaded at 9 into the shell 5.

The primary nozzle 11, together with a tapering valve rod 12 which is movable longitudinally through the nozzle orifice, forms a steam-controlling valve, the opening of the orifice being restricted as the valve is moved to the left. The rod 12 is guided by a sleeve-bearing 13 in the casting 7, with which the rod makes a sliding and approximately steam tight joint. The rod 12 terminates in the piston 14, which slides in a cylinder 15 formed integrally with the casting 7. The rod 12 and its attached piston 14 are urged to the right by a spring 16 coiled about the rod 12, and bearing against the casting 7, as shown. The movement of the rod 12 to the left is limited by the shoulder 17 which abuts against the casting 7. This is to prevent the tapered portion of the rod from sticking in the steam orifice of the primary nozzle 11 in case the rod were forced strongly to the left. The shoulder 17 is so positioned as to allow tight closure of the primary nozzle 11 by the rod 12. The space to the left of piston 14 is vented at 18 to relieve any pressure due to leakage past the bearing 13 or piston 14. The passage in casting 7 is drained by a pipe 19 to a drain cock 20, to remove any condensed steam, and a pipe 21 provided with a cock 22 serves as a similar drain for the right end of cylinder 15. The right end of cylinder 15 is closed by a screw plug or cylinder head 23, which makes a steam tight joint with the cylinder walls.

Threaded in cylinder head 23 is a rod 24

which serves as an adjustable abutment to limit the movement of piston 14 and its attached valve rod 12 to the right. The rod 24 is provided with a knurled head 25 and a 5 jam nut 26, so that it may be readily adjusted and locked in position.

The piston 14 makes a rather loose fit in the cylinder 15, so that there may be a slight leakage of steam past the piston. It is obvious that an increase of pressure in the cylinder 15 will tend to force the piston 14 and its attached valve rod 12 to the left, thus reducing the opening in primary nozzle 11, while similarly a reduction in pressure 15 causes movement to the right, and consequently opens the primary nozzle 11. Spring 16 is of such strength that it allows the piston 14 to move through its entire range when the pressure in 15 fluctuates 20 through the range of variation allowed in the boiler pressure; that is, if the boiler pressure may fluctuate five pounds the piston 14 will move throughout its entire range when the pressure in cylinder 15 rises from 25 zero pounds to five pounds gage.

It now remains to describe a mechanism which will cause the existence of approximately one pound pressure in the cylinder 15 for each pound the boiler pressure rises 30 above the desired minimum.

27 is a small pipe bringing steam from the boiler. It is screwed into a casting 28 which forms a seat for a valve 29 located in the casting 30 also screwed to castings 28. This 35 casting 30 is connected by a pipe 31 to the cylinder 15. The valve 29 is held upon its seat by a spring 32, and the load upon this spring is so adjusted that the valve 29 is held to its seat against the minimum pressure 40 desired to exist in the boiler, but when this pressure is exceeded the valve 29 will be forced from its seat against the spring's action, thus admitting steam to the casting 30, whence it will pass through the pipe 31 45 to the cylinder 15. The load on spring 32 is adjusted by means of a rod 33 threaded in casting 30, and carrying a swiveled block 35 bearing against the end of spring 32. A knurled head 34 mounted on the rod 33 50 serves as a means for turning the rod to adjust the spring.

The operation of the device is as follows: Let us assume that the desired average pressure for the boiler is 100 pounds, and that a 55 maximum fluctuation of five pounds may be allowed. In this case the spring 16 would be so chosen that the piston 14 would move through its entire range for a variation of five pounds, and the spring 32 would be so 60 adjusted that valve 29 would be lifted from its seat at a pressure of $97\frac{1}{2}$ pounds. Assuming the pressure in the boiler to be below $97\frac{1}{2}$ pounds and to be rising, it is obvious that valve 29 will be closed, and that due to

the leakage past piston 14 there will be a 65 pressure of zero pounds gage in the cylinder 15. As the pressure in the boiler, however, rises and exceeds $97\frac{1}{2}$ pounds, the valve 29 will be lifted from its seat and steam will flow into casting 30, and by pipe 31 to cylinder 15. Conversely, as the boiler pressure falls, the decreased tendency to open valve 29 will cause this valve either to close, or to tend to close. The leakage past the piston 14, aided by the condensation of steam in the 75 cylinder 15, will quickly reduce the pressure in this cylinder to the appropriate amount. It has been found that the above mentioned leakage and condensation are sufficient to secure the necessary reductions in pressure. 80 It has been found by experiment that each pound increase above pressure necessary to open valve 29 will cause approximately a corresponding pound increase of pressure in pipe 31, and cylinder 15, the increased pressure in casting 30 assisting in closing valve 29 as soon as this increased pressure is established. As the pressure in cylinder 15 increases, the piston 14 is forced to the left, 85 its movement being approximately proportional to the increase in pressure. Thus as the boiler pressure rises the opening of primary nozzle 11 is reduced, and the flow of steam to the blower consequently restricted. Hence the blowing action is diminished, and 90 less draft is supplied to the furnace. It is entirely feasible to have a fluctuation of five pounds in the cylinder 15 move the valve stem longitudinally $\frac{1}{8}$ of an inch. This considerable range of motion permits a very 95 100 nice adjustment of the orifice, and consequently a gradual fluctuation of the blower action with fluctuations in boiler pressure.

In most devices heretofore constructed the boiler pressure has been caused to act directly upon a regulating device, as for instance a damper regulator connected to a throttle on the blower steam pipe. Here, however, the spring or equivalent mechanism opposing the steam pressure must be 105 sufficiently strong to overcome the entire boiler pressure, and consequently the movement of the apparatus for a fluctuation of 110 five pounds is very slight. Any nice regulation of the blower action by such device is 115 therefore impossible, and the blower is merely turned on and off as the pressure fluctuates past a certain set point. This action is most unsatisfactory, and is avoided by my invention.

In the practical operation of my device the blower intensity is adjusted to the demands for steam made upon the boiler, the blower tending to maintain a practically uniform pressure in the boiler by a practically continuous operation of the blower. The intensity of the blowing, however, varies with the fluctuations in pressure, so that 125

the blower action is not intermittent, but the steam orifice is automatically adjusted to a mean opening appropriate to the existing boiler load, and varies but slightly from 5 this point in either direction during ordinary working. It will be noted, moreover, that the regulation of the steam flow occurs at the steam orifice, so that the steam is not throttled except at this orifice. This fact 10 results in a great saving over a device where the orifice remains constant, and the flow of steam is regulated by a valve interposed in the pipe leading to the orifice.

The use of a primary and a secondary 15 nozzle increases the efficiency of the device, but the controlling mechanism will function in the manner described regardless of the type of nozzle used.

In the above description I have called attention to the fact that slight leakage is 20 allowed to occur past the piston 14. It is not essential that this leakage should occur at this point, as any other means for accomplishing the purpose of gradually bleeding 25 pressure from the right end of cylinder 15 will accomplish the same result, and cause the device to function in the identical manner. It seems probable that there is a slight 30 flow of steam constantly past valve 29 when pressure exists in the right end of cylinder 15, but this flow, if it occurs, is very slight.

In the claims, I shall use the term "excess 35 pressure valve" to designate any valve that performs the function of valve 29; *i. e.*, creates a pressure on its low side equal approximately to the excess of boiler pressure 40 above the desired minimum.

Having thus described my invention, what I claim is:—

40 1. The combination of a boiler; a furnace; a draft tube adapted to furnish air to said furnace; a nozzle having a discharge orifice standing in line with said draft tube; connections for supplying an expansible fluid under pressure 45 to said nozzle; a movable nozzle-valve member adapted to vary the area of said orifice; a piston connected with said nozzle-valve member to move the same; a spring held valve connected with the boiler 50 and adapted to admit steam at reduced pressure against one face of the piston to urge the nozzle-valve in a closing direction; means for gradually venting such steam pressure from said piston face; and a spring opposing 55 the closing movement of the nozzle-valve member.

2. The combination of a boiler; a furnace; a draft-tube adapted to furnish air to said furnace; a nozzle having an orifice standing 60 in line with said draft tube; connections for supplying an expansible fluid under pressure to said nozzle; a movable nozzle valve member adapted to vary the area of said orifice; a piston connected with said nozzle valve

member to move the same; an excess pressure valve adapted to open under boiler pressure to admit steam from the boiler against one face of the piston to urge the nozzle valve member in a closing direction; a spring adapted to urge said excess pressure valve in a closing direction; means for adjusting the stress on said spring; means for gradually venting said pressure from the piston face; and a second spring opposing the closing movement of the nozzle valve 75 member.

3. The combination of a boiler; a furnace; a draft-tube adapted to furnish air to said furnace; a nozzle having an orifice standing in line with said draft tube; connections for supplying an expansible fluid under pressure to said nozzle; a conical valve member axially movable through said discharge orifice to vary the area thereof; an adjustable stop adapted to limit the opening movement of the nozzle valve member; a piston connected with said conical valve member to move the same; an excess pressure valve adapted to open under boiler pressure to admit steam from the boiler against one face of the piston to urge the conical valve member in a closing direction; a spring adapted to urge said excess pressure valve in a closing direction; mechanism for adjusting the stress on the spring; means for slowly venting pressure from the piston face; and a second spring adapted to oppose closing movement of the conical valve member.

4. The combination of a boiler; a furnace; a draft tube adapted to furnish air to said furnace; a nozzle having an orifice standing in line with said draft tube; connections for supplying an expansible fluid under pressure to said nozzle; a valve adapted to control the flow of such fluid through said nozzle; a piston operatively connected with said valve; an excess pressure valve adapted to open under boiler pressure to admit steam from the boiler to one side of said piston to move the first named valve in a closing 100 direction; a spring adapted to urge the excess pressure valve in a closing direction; means for slowly venting pressure from said piston; and a spring adapted to oppose the closing movement of the first named valve. 105

5. The combination of a boiler; a furnace; a draft tube adapted to furnish air to said furnace; a nozzle having an orifice standing in line with said draft tube; connections for supplying an expansible fluid under pressure 110 to said nozzle; a valve adapted to control the flow of such fluid through said nozzle; a piston operatively connected with said valve; an excess pressure valve adapted to open under boiler pressure to admit steam from the boiler to one side of said piston to move the first named valve in a closing 115 direction; a spring adapted to urge the ex-

cess pressure valve in a closing direction; means for adjusting the stress in said spring; means for slowly venting pressure from said piston; and a spring adapted to 5 oppose the closing movement of the first named valve.

In testimony whereof I have signed my

name to this specification in the presence of two subscribing witnesses.
